UNITED STATES PATENT OFFICE

2,584,790

SWITCHING CIRCUIT

Charles Peter Cooper, Chelmsford, and Guy Edward Williamson-Noble, London, England, assignors, by mesne assignments, to Radio Corporation of America, New York, N. Y., a corporation of Delaware

Application April 8, 1947, Serial No. 740,222
In Great Britain December 18, 1945

Section 1, Public Law 690, August 8, 1946
Patent expires December 18, 1965

4 Claims. (Cl. 250—27)

1

This invention relates to voice and like signal operated switching circuit arrangements and, though not limited to its application thereto it is particularly adapted for use in radio telephone systems for automatically switching on the carrier for speech and switching it off when speech ceases. Such automatic switching is frequently required for example in duplex systems where the same carrier wave length is employed for speech in both directions.

The practical requirements to be satisfied in such a voice operated switching system are very onerous. Firstly it must be very quick acting for if the carrier be not fully switched on by the initial consonant of the first word "clipping" of the speech will occur at each switching on especially if the consonant is of low energy content. In practice this requirement involves that an audio signal about 30 db, below that required for full modulation should bring the transmitter fully on the air not more than 2 milli-seconds after said signal reaches the modulation circuits. The common expedient of meeting this difficulty by inserting a delay line between the audio input and the modulation circuits is objectionable on the ground of expense and, on this ground, a quick acting relay is much to be preferred.

A second difficulty is that of noise. Noise outside the speech band or other band of audio-frequencies to be handled can be eliminated by means of a filter but noise including background noise in the microphone room must be below the level required for switch operation. This involves that if sensitivity be increased too much the transmitter may be switched on by noise which may further hold the carrier on after speech has ceased, whereas it is essential in most systems, such as a duplex system with common carrier frequency for two-way working, that release should occur—i. e. the carrier be switched off—on cessation of speech. In practice a difference of only 2 db is usually required between operation and release and considerable difficulty is experienced, in known arrangements, in securing reliable operation with so small a difference of level.

If a carrier is switched fully on in 2 milli-seconds or less, a light click is heard on the receiver headphones and it is therefore desirable to reduce the number of switchings as far as possible. For this reason a so-called "hang-over" circuit, giving a hang-over time of about 0.1 second is usually required to hold the carrier on for complete phrases of speech as distinct from allowing release in the short inter-syllabic and inter-word pauses of ordinary speech. Ideally this

2

hang-over time should be independent of the level and duration of a speech phrase and in practice a variation of about 1.5 to 1 is all that is permissible.

5 The hang-over circuit will normally have a logarithmic law of voltage decay and accordingly if it be applied direct to the transmitter control circuits a transient condition will arise when the transmitter is nearly off, the normal hum or 10 noise on the carrier then giving a high degree of modulation causing a whistle or grunt on the receiver signal. The hang-over circuit therefore normally operates by switching off the carrier at the end of the hang-over period through a 15 relay provided for the purpose—a further complication.

In many cases there is the further requirement that a local receiver has to be rendered insensitive just before the carrier comes on and rendered 20 sensitive again after the carrier has gone off. This involves the provision of another set of circuits if the transmitter is controlled by an electronic type of switch.

The present invention seeks to provide improved and reliable switching circuit arrangements capable of satisfying the practical requirements with a minimum of complication and operating through a high speed switch—preferably a high speed electro-magnetic relay—to perform 25 the necessary transmitter (and, if required, local receiver) circuit changes, the switching circuit arrangements provided by the said invention securing relay or switch change over in the required short time of about 2 milli-seconds or less.

35 According to this invention a voice or like signal operated switching circuit arrangement comprises a high speed switch or relay controlled by the output current of a controlling electron discharge tube circuit; a limited pulse providing 40 electron discharge tube circuit connected with the controlling circuit to cause it to produce a predetermined changed output current (preferably zero) in response to a pulse, said pulse producing electron discharge tube circuit having two 45 conditions of stability (multivibrator circuit) and being adapted to produce an output pulse substantially of pre-determined amplitude independent of input amplitude above a pre-determined minimum level; and a phase splitting circuit fed 50 with the voice or like actuating signals and providing input to said pulse producing circuit to cause it to produce a pulse in response to each half wave of actuating signal input above a pre-determined minimum level irrespective of the 55 polarity of the half-waves. Preferably a delay

circuit adapted, in discharged condition, to hold the controlling circuit near said pre-determined output current between pulses is provided, said delay circuit being arranged to be discharged by the first pulse as rapidly as possible.

As is well known, practically any transmitter can be arranged to be switched on by earthing one point in its keying circuit and a receiver can also usually be arranged to be rendered sensitive by earthing one point thereof. In the preferred way of applying the invention, therefore, the high speed switch or relay is used to put on and take off these earth connections: by employing a suitable electro-magnetic relay with an earthed tongue both a transmitter and local receiver may be controlled by the same relay.

The invention is illustrated in the accompanying drawing which shows diagrammatically a preferred embodiment thereof.

Referring to the drawing, audio input is applied through a transformer T1 and adjustable potentiometer P1 between the control grid and cathode of a tube V1, shown as a pentode, the movable point on the potentiometer being connected to the grid and its ends being connected across the secondary of the transformer T1. One end of this secondary is connected through a condenser C1 to the cathode and through a resistance R2 to a junction point with a resistance R3 whose other end is connected to the cathode. This junction point is taken to earth through a resistance R4 and through a condenser C3 to the suppressor grid of a pentode V3, said suppressor grid being connected to earth through a resistance R1. The screen and suppressor grids of tube V1 are strapped to its anode which is taken through a resistance R5 to a source of high tension potential (not shown) connected at HT+. This anode is also connected through a condenser C2 to the suppressor of a pentode V2, said suppressor being connected to earth through a resistance R6. The cathodes of tubes V2 and V3 are connected together and to their respective control grids; the screen grids are connected together and through a resistance R9 to HT+; and the anodes are connected together and through a resistance R8 to HT+, the common anode connection being taken through a resistance R10 in parallel with a condenser C4 to the control grid of a pentode V4, said grid being connected through a resistance R11 to earth and to the negative terminal HT- of the high tension supply. The screen grid of tube V4 receives potential from HT+ through a resistance R12 and is connected to earth through condenser C5 while its anode is connected directly to HT+ and its suppressor grid is strapped to the cathode, the said cathode being connected directly to that of a further pentode V5 and through two resistances R13 and R14 in series to ground. The cathode of V3 is connected to the junction point of resistances R13 and R14. The anode and all three grids of V5 are connected together and to earth through a condenser C6 and, through resistances R15 and R17 (the latter preferably adjustable) to the cathode of a pentode V6. This cathode is connected to earth through a resistance R18 which is preferably adjustable. A condenser C7 is in parallel with resistance R18. The control grid of V6 receives input directly from the common grid-anode point of V5 and its screen grid is connected to HT+ its suppressor grid being connected to the cathode and its anode being connected to HT+ through the winding S1 of a high speed electro-magnetic relay hav-

ing an earthed tongue T and "mark" and "space" contacts M and S. The usual bypass condenser C8 is connected across the HT.

In the absence of input V4 passes a large anode current and V3 a small one but if the suppressor grid of V3 is driven positive the current through R8 increases tending to depress the control grid of V4 but, since this tube is already drawing grid current, its control grid voltage and anode current do not appreciably change until its control grid current ceases when the current in R13 R14 falls, reducing the cathode voltage of V3, increasing its anode current and thus giving a cumulative action still further reducing, through V4, the current through R13 R14. The anode current of V4 is thus rapidly cut off and that of V3 increased at the expense of screen current. The speed of this change over is increased, by the provision of condenser C4 which reduces the effect of stray capacity in the grid circuit of V4. When the suppressor of V3 falls to a certain value below that required for initiation of the foregoing action the sequence is reversed and the cathode-coupled multivibrator circuit constituted by the circuits of V3 and V4 reverts to the original state. Thus a sine wave input to the suppressor of V3 will produce across R13 and R14 rectangular waves of substantially constant amplitude so long as the input is sufficient to drive V4 from the grid current condition. If it is insufficient there is virtually no output. As so far described an initial positive swing on the suppressor of V3 will operate the multivibrator but an initial negative swing will not. It is for this reason, that is to say to ensure rapid triggering action whatever the polarity of the initial half wave, that the tube V2 is provided, this tube being connected in practically the same manner as V3 acting similarly on V4 except that, owing to the phase splitting action of V1, when the input to V3 is negative that to V2 is positive. Its provision modifies somewhat the wave shape of the output from V4 but not so as to upset the operation of the delay circuit which, as will be apparent later, requires only that the maximum negative excursion of the wave shall be independent of the input to the combination V2 V3 V4 which, as will now be seen, acts as what may be termed a limiter multivibrator.

The delay circuit comprises V5, which acts as a diode in a resistance-capacity network. When the voltage across R13 and R14 suddenly reduces, C6 is rapidly discharged through V5, R13 and R14, thus reducing the anode current of V6. This operates the relay to close the "mark" contacts. C7, by preventing rapid variations in cathode voltage of V6 speeds up this fall of anode current resulting in about a 3 to 1 increase in operating speed without materially affecting release (movement to "space") speed. When the input to the multivibrator limiter falls below the threshold, the cathode of V5 returns to normal and this tube ceases to conduct, C6 then re-charging through R16 and R17 from the voltage developed across R18. As C6 re-charges, the grid voltage and anode current of V6 increases, causing an increase nearly equal to the grid voltage increase in the voltage across R18, thereby keeping almost constant voltage across R16 and R17. This effect increases by a factor of nearly 10 to 1 the time taken by C6 to recharge to a given voltage, thereby allowing, for a given release time, the use of a condenser C6 of a value of about one tenth that which would be required were it charged from a constant voltage source through

the same value of resistances R16 R17. It follows, accordingly, that discharge time-constant (and consequently operating time) is reduced in about the same ratio. When the anode current of V6 reaches a certain value the relay operates to open the "mark" contacts at a time interval (after the cessation of audio input) which is controlled by adjustment of R17. Shortly after this the voltage across C6 reaches a value which allows V5 to conduct thereby preventing further increase in grid voltage and anode current of V6. R18 is used to set the current through the relay in absence of input signal to a value just above that required to make the relay operate. This current varies slightly from relay to relay being dependent on the gap in the iron circuit and stiffness of springs. A fine setting is desirable to enable the relay to respond very rapidly by opening when the current through its coil starts to fall. An illustrative set of values of the different electrical components are:

P1=100 k. ohms; R2=300 k. ohms; R3=1 k. ohm; R4=30 k. ohms; R5=30 k. ohms; R6=100 k. ohms; R7=100 k. ohms; R8=300 k. ohms; R9=30 k. ohms; R10=300 k. ohms; R11=100 k. ohms; R12=30 k. ohms; R13=500 ohms; R14=700 ohms; R16=100 k. ohms; R17=500 k. ohms (max.); R18=5 k. ohms (max.); C1=0.1 μ f.; C2=.01 μ f.; C3=.01 μ f.; C4=10 μ f.; C5=0.1 μ f.; C6=0.1 μ f.; C7=1 μ f.; C8=1 μ f.

The relay operates with a current of about 8 ma. The H. T. supply is 300 volts.

The embodiment described has many important advantages: The use of the relay allows both transmitter and local receiver to be controlled by one set of circuits and renders the apparatus applicable to any normal telegraph-telephone transmitter; the time to operate can be made under 2 milli-seconds and is almost independent of input level once a certain minimum is exceeded; a very small fall in level below minimum causes a release; the hangover time (given by the delay circuit) is almost independent of input after a first period equal in practice to a maximum of about 10 milli-seconds; no relay specially provided to switch off the transmitter alone is required; and no large preamplification or high performance A. V. C. chain is required so that stable operation from a low cost, low consumption small installation is obtainable. In fact, in an experimental installation a tube consumption of only about 30 ma. at 200 volts with an overall size of only 4" x 11" x 5" (including input transformer, input level potentiometer and filter to cut off frequencies below 700 cycles per second) have been attained with an ability to operate from -36 db on 1 mw. corresponding to a full modulation level of -6 db on 1 mw.

Having now particularly described and ascertained the nature of our said invention and in what manner the same is to be performed we declare that what we claim is:

1. A voice operated switching system comprising a source of message signals providing a waveform having positive and negative half waves, a phase splitting circuit coupled to said source and comprising an electron discharge device having an anode, a cathode and a grid, a transformer coupling said source to said grid and cathode, a limiter comprising first, second and third electron tubes each including a grid, a cathode and an anode, a connection between the anode of said device and the grid of said first tube, a connection from the cathode of said device to the

grid of said second tube, direct connections between the cathodes of said first and second tubes, direct current connections including resistors respectively extending from the cathodes of said device and said third tube to the cathodes of said first and second tubes, a resistor shunted by a condenser connected between the anodes of said first and second tubes and the grid of said third tube, whereby said limiter produces a pulse in response to each half wave of the waveform applied by said source to said device about a predetermined minimum irrespective of the polarity of the half waves, a fourth vacuum tube coupled to the output of said third tube and controlled by the pulses produced by said limiter, and a load device controlled by the output current of said fourth tube.

2. A voice operated switching system comprising a source of message signals providing a waveform having positive and negative half waves, a phase splitting circuit coupled to said source and comprising an electron discharge device having an anode, a cathode and a grid, a transformer coupling said source to said grid and cathode, a limiter comprising first, second and third electron tubes each including a grid, a cathode and an anode, a connection between the anode of said device and the grid of said first tube, a connection from the cathode of said device to the grid of said second tube, direct connections between the cathodes of said first and second tubes, direct current connections including resistors respectively extending from the cathodes of said device and said third tube to the cathodes of said first and second tubes, a resistor shunted by a condenser connected between the anodes of said first and second tubes and the grid of said third tube, whereby said limiter produces a pulse in response to each half wave of the waveform applied by said source to said device above a predetermined minimum irrespective of the polarity of the half waves, a fourth vacuum tube coupled to the output of said third tube and controlled by the pulses produced by said limiter, a delay circuit between the output of said limiter and the input of said fourth vacuum tube, and a load device controlled by the output current of said fourth tube.

3. A voice or like signal operated switching system, comprising a source of signals providing a waveform having positive and negative half waves, a phase splitting circuit coupled to and fed by said source and providing an output half wave in response to each half wave of signal from said source, said phase splitting circuit comprising an electron discharge device having two output terminals at which appear output half waves of opposite phase in response to each half wave of signal from said source, an electron discharge device cathode-coupled multivibrator circuit having two conditions of electrical stability coupled to the output of said phase splitting circuit and providing pulses of substantially constant amplitude independent of the amplitude of the half waves supplied thereto by said phase splitting circuit above a predetermined minimum level, an electron discharge tube circuit coupled to the output of said multivibrator circuit, said tube circuit being acted on by said pulses to produce therein, in response to said pulses, a predetermined changed output current, and a load device coupled to the output of said tube circuit and responsive to said predetermined changed output current.

4. A voice or like signal operated switching

system, comprising a source of signals providing a waveform having positive and negative half waves, a phase splitting circuit coupled to and fed by said source and providing an output half wave in response to each half wave of signal from said source, said phase splitting circuit comprising an electron discharge device having two output terminals at which appear output half waves of opposite phase in response to each half wave of signal from said source, an electron discharge device cathode-coupled multivibrator circuit having two conditions of electrical stability coupled to the output of said phase splitting circuit and providing pulses of substantially constant amplitude independent of the amplitude of the half waves supplied thereto by said phase splitting circuit above a predetermined minimum level, an electron discharge tube circuit coupled to the output of said multivibrator circuit, a delay circuit positioned between said multivibrator and said tube circuit, said tube circuit being acted on by said pulses to produce therein, in response to said pulses, a predetermined changed output current, and a load device coupled to the

8
output of said tube circuit and responsive to said predetermined changed output current.
